UNITED STATES PATENT OFFICE.

HERBERT FRANK SCORIS AND MILE LARO, OF ST. PAUL, MINN.

PHOTOGRAPHIC-PRINTING DEVICE.

Application filed July 17, 1920. Serial No. 387,047.

To all whom it may concern:

Be it known that we, HERBERT FRANK Scoris and MILE Laro, citizens of the United States, and residents of Sleepy Eye, county of Brown, State of Minnesota, have invented certain new and useful Improvements in Photographic-Printing Devices, of which the following is a specification.

This invention relates to improvements in devices used in the art of printing from photographic negatives and has for its principal object the production of an apparatus in which the printing may be accomplished by artificial light.

Another object is to provide such a photographic printing device in which the presser-back which holds the printing sheet of sensitized paper against the glass is formed of a plurality of resiliently mounted sections.

Other objects of the invention will more fully appear from the following description and accompanying drawings and will be pointed out in the annexed claims.

In the drawings:

Figure 1 is a longitudinal section through the printing device.

Figure 2 is a plan view.

Figure 3 is a view in side elevation, showing the presser-back in raised position.

Figure 4 is a section on the line 4-4 of Figure 1.

This novel device is adapted to be mounted upon a suitable support 1, such as a table top. The support 1 is adapted to have an opening 2 cut therein and suitable luminescent means are provided beneath the opening. It is customary in this art to provide an electric lamp 3 having suitable connection with a source of electricity, and adapted to be turned on and cut off upon closure and opening of the usual presser-back. Such common practice is here followed.

The presser-back in this novel device is preferably composed of three sections, a base section 4, a rear section 5 and a front section 6. The front section 6 is pivotally secured to the rear section 5 by means of the hinges 7, while the rear section 5 is pivotally supported on the base section 4 by means of the hinges 8. The base section 4 is preferably resiliently secured to the support 1, as by means of screws 9 passed through the base section 4 and received in the support 1. A coiled spring 10 is mounted on each screw 9 and is held between the

washers 11 and 12 carried by the screws 9. These coiled springs function to hold the base section 4 on the support 1 but permit of some resiliency to take up any shock resulting from movement of the presser-back and to afford some adjustment, if necessary, to accommodate any variant thickness of glass positioned over the opening 2. The front section in this selected embodiment of the invention is of a size equal to that of the front section 6. In the construction of this device the opening 2 in the support is preferably formed adjacent the edge of the support top and a latch member 14 is carried by the support top and carrying a terminal hook 15 is adapted to engage the under face of the support top. This latch member is pivotally mounted on the section 13 and functions, when the hook 15 is in the engaged position, to hold under static pressure the presser-back in position over the opening. The surface of the table top adjacent the opening is preferably marginally cut away to provide a seat for the translucent means covering the opening which affords a support for the photographic printing material such as a film sensitized paper, etc., although it is to be understood that the term "translucent means" may include an exposed photographic plate upon which the sensitized paper is directly placed. Such translucent means is here shown as a glass 16 placed over the opening and upon which is placed the film from which the usual superposed sheet of sensitized printing paper receives the varied light rays forming the photographic reproduction. The latch 14 is normally held in a position closely against the front edges of the section 6 and 13. The latch member is apertured to permit the passage therethrough of a coiled spring 17, one end of which is secured to the latch and the other end to a pin 18 secured to the under portion of the superimposed section 13. The upper face of the front section 6 is preferably grooved to afford space between such section and the bottom face of the superimposed section 13 for the spring 17.

A printing device of this contact type is adapted to be operated at high speed and therefore means are provided so that upon the release of the locking latch the presser-back sections which cover the opening will be automatically raised so that the paper print and film may be removed. Not only

is provision made for the rapid automatic movement of the presser-back into inoperative or lifted position, but also provision is made so that the positioning of the presser-back on the glass is under sufficient tension to hold the print and film in position. In devices of this type which use a sectional presser-back, it frequently happens that the pressure upon the glass by the sudden closing of the presser-back under tension cracks the glass. In this novel construction, the downward tension upon the front section, which covers the major portion of the table opening, is applied substantially to the whole area of this front section. Therefore, the superimposed section 13 is mounted on the front section 6 so that its downward force is resiliently applied to the section 6. For this purpose, spring means, such as leaf springs 19 are secured by the screws 20 to the under face of the superimposed section 13. The terminal portions of the leaves engage the upper surface of the front section 6.

25 A system of spring-controlled levers is employed, not only to place a pressure upon the presser-back sections when they are in aligned, locked position, but also to effect automatic raising of the presser-back to a predetermined, lifted position. A shaft 21 is rotatably borne in brackets 22 secured to the upper surface of the base section 4. A shaft arm 23 is secured to, and is rotatable with, this shaft 21. The arm 23 is permanently secured to a pivot pin 24 carried adjacent the rear portion of a front arm 25. The forward end of this front arm is pivotally secured to a bracket 26 mounted on the upper surface of the superimposed section 13. This lever system is under tension suitable to effect the lifting of the presser-back upon unlatching. A torsion lift spring 27 is coiled upon one portion of the shaft 21 and has one end 28 resting against the upper surface of the base section 4, while the other end of the lift spring is inserted in an aperture formed in the shaft arm, so that when the presser-back is manually lowered to operating position, this lift spring is placed under tension which, on latch release, lifts the back. A second torsion spring 29 is coiled upon another portion of the shaft 21 and functions as a recoil spring to absorb the jar of the sudden tensioned movement of the presser-back upon release. One end of the recoil spring 29 is secured in an aperture in the shaft arm 23 while its other end 30 is adapted alternately to rest upon the top surface of the base section (Figure 3), or to be out of contact therewith (Figure 1). When the presser-back is in the position shown in Figures 1 and 2, the end 30 of the recoil spring 29 is out of contact with the surface of the section 4; but, when 65 the back is released and moves toward the position shown in Figure 3, the end 30 contacts with the surface of the section 4 and the resultant tension-coiling of the spring brings the presser-back to rest substantially in the position shown in Figure 3.

70 A bar 31, having an offset foot 32, is rigidly secured to the shaft arm 23 adjacent its pivotal mounting on the front arm. The foot of this bar is adapted to engage, when the presser-back is moved to operative locked position, the top surface of the section 5 in order to hold it firmly against the adjacent portion of the glass-covered opening. The contact between the foot of this bar and the section 5 is preferably effected through a leaf spring 33 secured to the upper surface of the section 5.

75 When the presser-back is in operative position and the latch is released, the back automatically is lifted. Such automatic lifting is not broadly novel. But, it has been found in the use of devices of this general type that when presser-backs are thus automatically lifted, a partial vacuum is created and the film and printing material are displaced. Hence, it is desirable to provide a means which will cause the relative pivotal movement of the front and rear sections of the presser-back so that the front section will tend to be raised from the glass-covered opening before the rear section and such vacuum tendency destroyed. This is one of the functions of the spring 34. This spring causes the front and rear sections to assume the angular relation to each other, 90 when the back is in lifted position, as is shown in Figure 3. When the presser-back is in closed operating position, this coiled spring 34 is under tension, as one of its ends is held by the eyelet 35 on the superimposed section 13, while its other end is held by the eyelet 36 on the upper surface of the rear section 5. As the longitudinal axis of this spring is above the axis of the pintles of the hinges 7, joining the front section 6 and the rear section 5, this spring tends to break these hinges when the back is released and lifted by the tensioned lever system. Any lifting force imparted to the superimposed section 13 is imparted to the 105 section 6 by the screw 41 which is received in threaded engagement in the section 6 and is slidably in an aperture formed in the superimposed section 13. A washer 42 on this screw between its head and the upper 110 surface of the section 13 lifts the screw and the section 6 when the superimposed section 13 is lifted by the lever system.

115 A supplemental spring 37 is preferably secured to the terminal portion of the front arm 25 and to the arm 23 adjacent the shaft. When the back is in closed position, this spring is not under tension, as is indicated in Figure 1; but, when the back is lifted, it is placed under tension which substantially 120 130

5 prevents the front sections forming too acute an angle with relation to the rear section, which would normally be the case due to the influence of the spring 34. This supplemental spring 37 thus limits the angular relation of these adjacent presser-back sections when the back is in lifted position whereby the sections are held in a predetermined lifted position. This desired position is such that, upon manual movement of the back to closed position upon the glass, the section 5 first contacts with the glass and holds the film, printing paper, masks, etc., in positioned relation on the glass in 10 full view of the operative so that it is easy to determine that proper placement will be retained. Further the section 5 assures a firm engagement on the paper, etc. while section 6 is still in lifted position, permitting easy withdrawal of the operative's hand which has adjusted the printing paper, etc. This is accomplished by aid of the coiled spring 34.

As it is common to provide, in devices of 25 this kind, make-and-break electric switches in circuit with an electric lamp or lamps 3, such switch means 38 is only indicated and the usual circuit wiring is omitted herein. However, there is represented in the drawings a spring-actuated plunger 39 adapted 30 to control the switch 38. This plunger is adapted to be inwardly pressed, against tension of its spring 40, by this latching member when in latched position. The spring 35 40 returns the plunger 39 to outward, circuit-breaking position, upon latch release.

There is thus provided a novel photographic printing device which is simple and accurate in operation and lends itself to 40 rapid printing. The normal, lifted position of the back sections is such that the hand of the operator which is positioning the printing material is not forced into a cramped and view-obscuring position preparatory to 45 completely closing the back, and the latching and lifting means are such that a rearward blow from any front angle immediately causes the automatic lifting of the back to a definite position from which it may quickly 50 be returned to closed position upon re-positioning of film and paper, etc.

It is to be understood that the construction disclosed herein is illustrative but not restrictive and that the same may be modified within the meaning and scope of the 55 claims which follow:

Having thus described our invention, what we claim as new, and desire to secure by Letters Patent, is:

60 1. A photographic printing device including, a support provided with a negative-receiving opening, luminous means under the opening, translucent means on the support covering said opening to support the photographic printing material, a presser-back

65 pivotally mounted on the support and adapted to close said opening and to be lifted therefrom, latching means to retain the back in closed position, a lifting spring operatively connected to said back to lift the 70 back upon latch release, and recoil means to work against said lifting spring after the back is lifted whereby the back is normally held above and adjacent the opening.

2. A photographic printing device including, a support provided with a negative-receiving opening, luminous means under the opening, translucent means on the support covering the opening to support the photographic printing material, a presser-back 80 movably mounted on the support and adapted to close the opening and to be lifted therefrom, latching means to retain the back in closed position, a shaft pivotally mounted on said support and connected to said 85 presser-back, a torsion spring on said shaft to lift the back upon latch release, and a second torsion recoil spring on said shaft to work against the lifting spring after the back is lifted whereby the back is normally 90 held above and adjacent the opening.

3. A photographic printing device including, a support provided with a negative-receiving opening, luminous means under the opening, translucent means on the support 95 covering the opening to support the photographic printing material, a presser-back pivotally mounted on the support and adapted to close the opening and to be lifted therefrom, the presser-back being formed of 100 a plurality of sections hinged together, a superimposed member on one of the sections substantially covering the same, latching means pivotally secured to said member and adapted, upon movement of the presser-back 105 to closed position, releasably to engage the support whereby the presser-back is held under pressure in closed position, and resilient means between said superimposed member and section whereby the front section is 110 resiliently held in closed position.

4. A photographic printing device including, a support provided with a negative-receiving opening, luminous means under the opening, translucent means on the support 115 covering the opening to support the photographic printing material, a presser-back movably mounted on the support and adapted to close the opening and to be lifted therefrom, the presser-back being formed of 120 a plurality of sections hinged together, a superimposed member on one of the sections substantially covering the same, latching means pivotally secured to said member and adapted, upon movement of the presser-back 125 to closed position, releasably to engage the support whereby the presser-back is held under pressure in closed position, tension means mounted upon said support and connected to said superimposed member and 130

adapted, upon release of the latching means, to lift the presser-back to open position.

5. A photographic printing device including, a support provided with a negative-receiving opening, luminous means under the opening, translucent means on the support covering said opening to support the photographic printing material, a presser-back pivotally mounted on the support and adapted to close the opening and to be lifted therefrom, the presser-back being formed of a plurality of sections hingedly connected, latching means secured to the presser-back and adapted releasably to retain the back in closed position, a lever system adapted to

lift the back upon latch release, tension means connected to adjacent presser-back sections to cause them to assume angular relation and break the tendency to vacuum when the back is lifted, and tension means 20 on said lever system to cooperate with said section tension means to limit said angular relation whereby the presser-back sections are held in predetermined lifted position.

In witness whereof, we have hereunto set 25 our hands this 7th day of July, 1920.

HERBERT FRANK SCOBIE,
MILO LADD.

Witness:

H. C. DOMEIER.
